Ernest H. Johnson

UNITED STATES PATENT OFFICE.

WILLIAM J. KENT, OF BROOKLYN, NEW YORK, ASSIGNOR TO THE MECHANICAL RUBBER COMPANY, A CORPORATION OF NEW JERSEY.

MACHINE FOR MAKING ROLL-PACKING.

1,362,106.

Specification of Letters Patent. Patented Dec. 14, 1920.

Application filed January 2, 1920. Serial No. 349,124.

To all whom it may concern:

Be it known that I, WILLIAM J. KENT, a citizen of the United States, residing in the borough of Brooklyn, city of New York, county of Kings, and State of New York, have invented certain new and useful Improvements in Machines for Making Roll-Packing, of which the following is a full, clear, and exact description.

10 This invention relates to a machine for making rolled packing, and it may be used for rolling packing either with or without a core.

Machines at present in use for this purpose consist of a revolving drum having a segmental apron spaced therefrom, and in operation a core is placed at the edge of a strip of packing, the packing given a number of rolls around the core and the roll then inserted between the apron and drum, the rotation of the drum with respect to the apron serving to finish the rolling of the packing. In the case of a coreless packing the operation is similar except that the packing is rolled up directly upon itself. When the roll is inserted between the drum and apron it is necessary for the operatives to pass along the front of the drum and press in the roll throughout its length between the apron and drum with an implement. As the success of this operation depends entirely upon the skill and care of the operator the quality of the packing varies considerably due to the uneven insertion of the roll, the finished product being hard where pushed in too far and soft where not pushed in far enough. In addition the faces of the drum and apron are both polished and become very smooth from use and as a result the friction cloth is frequently not evenly gripped causing the cloth to kink, thereby producing a defective roll of packing. The prior machines are also very noisy in operation, as the discharge end of the apron is provided with stops adapted to contact with the frame of the machine and prevent the apron from striking the drum as a roll of packing is discharged from between the drum and apron. This constant pounding of the stop against the frame causes considerable noise during operation.

An object of the present invention is to provide a machine capable of producing a larger quantity of a more uniformly rolled packing.

Another object is to provide means for evenly introducing the packing or the core and packing to the machine.

A further object is to provide means for giving the core and packing an initial partial roll as they are inserted in the machine, which means is adjustable for different thicknesses of core and packing.

A still further object is to provide a machine operating with greater quietness.

A still further object is to provide an improved means for supporting and adjusting the apron of the machine.

In the drawings:

Figure 1 is a front elevation of the machine with its operating table removed.

Fig. 2 is a vertical section through the machine.

Fig. 3 is a perspective showing a core with a packing strip partially rolled thereon.

Fig. 4 is a perspective of a sheet of packing, showing the manner of starting the roll when a core is not used.

Referring to the drawings, the numeral 1 is applied to the side frames of the machine. 80 Journaled in the frames is a shaft 2 carrying the drum 3, a pulley 4 being secured to the end of the shaft and driven by a belt from a desired source of power. It is obvious, however, that the drum can be rotated by any suitable means. Extending between the side frames at their tops is a shaft 5 having eccentric portions 6 journaled in spaced bearing brackets 6'. Outside the side frames the shaft carries disks 7 each having a series of apertures 8 therein, which apertures by the rotation of the disks may be in turn brought in register with openings 9 in the side frames, pins being inserted in the openings 9 and aligned apertures 8 to secure the disks in adjusted position. Beyond the disks 7 the shaft is provided with squared ends 10 by which it may be readily turned. A series of links 11 are hung upon the shaft 5 by means of eyes 12 at their upper ends, 100 the links being extensible by means of turn buckles 13 disposed at their middle portions. At the lower end of each link is an eye 14 adapted to pass between apertured brackets 15, the brackets being secured to the eyes by 105 bolts 16 passing through the apertures in the brackets and the eyes and held in place by nuts 17. Secured to the brackets 15 is a curved segmental apron 18 having upwardly turned sides 19. Weights may be disposed

110

in this apron between the upturned sides 19 to secure the desired pressure of the apron upon the roll. The inner surface of the apron 18 is serrated at its forward end as shown at 20 for a purpose to be later described. Chains 21, in the present instance two in number, are secured to the bottom or rear end of the apron, the upper ends of the chains being secured to threaded pins 22 passing through the upper part of the frame, which pins are held in adjusted position therein by means of the nuts 23 and 24. It is obvious that any desired number of links 11 and chains 21 may be used. A crossbar 25 extends between the side frames at the front of the machine and secured to this crossbar is a series of apertured supporting lugs 26. An eccentric bolt 27 is secured in each apertured lug by nuts 27', by loosening which it may be adjusted. Pivottally suspended on each bolt is an angled piece 28, the several angled pieces being connected by a bar 29 serving as a handle and also as a brace. Secured to the forward ends of the angled pieces 28 is an angled plate or pusher 30, the rearwardly directed edge of which is rounded as shown at 31. The opposite ends of the angled pieces carry counter weights 32. Also secured to the crossbar 25 is a curved core table or shelf 33 in which the cores when used are placed for ready access by the operator. At the front of the drum a table 34 is disposed upon which the strip of packing may be placed and given its initial roll, either with or without a core, before insertion in the machine. At the rear of the machine an inclined surface 35 is disposed for carrying away the finished rolls of packing.

In operation a core 36 is disposed at the edge of a strip of packing 37 and if desired the packing is given a partial roll around the core as shown in Fig. 3, although this is not essential. The core and packing strip are then inserted between the apron and drum, and the operative by swinging the plate or pusher 30 downwardly by the handle 29 causes the rounded edge 31 of the plate to strike the core 36 slightly below its middle portion. Upon pushing the plate 30 inwardly the core and packing are evenly inserted between the drum and apron throughout their length, and at the same time the edge 31 causes the core to be rotated by pressure on its bottom portion while the upper portion or the edge of the packing is frictionally held by the serrated surface 20. As it is necessary, in order to give the core and packing strip this partial rotation, that the plate 30 strike below the central portion of the core 36, or in the case of a coreless roll below the center of the roll, it is evident that the plate must be adjusted for different diameters of core and thicknesses of packing.

As the machine is run for long periods on the

same size of core and packing this adjustment need not frequently be made. However when necessary it is accomplished by loosening the nuts 27' and rotating the eccentric bolts 27 thereby raising or lowering the pivotal point of the plate 30, the nuts 27' being tightened again when the desired adjustment has been made. The upper or forward end of the apron can also be adjusted to vary its spacing from the drum in accordance with different sizes of cores or packing. This can be accomplished by means of the turn buckles 13 or by rotation of the shaft 5, the shaft being retained in adjusted position by means of pins inserted through the apertures 9 in the frame and 8 in the disk 7, as before stated. The rear end of the apron may be adjusted by means of the nuts 23 and 24 on the pins 22 carrying the chains 21. It will be noted that by means of the chains 21 the use of stops on the apron 18 contacting with the frame is obviated, thus doing away with the noise caused by the contact of the stops with the frame.

If coreless packing is to be made, a sheet of the packing material is manually rolled up on itself at one edge as shown in Fig. 4 and the rolled up portion evenly introduced between the drum and apron by means of the plate 30, and the rolling is then completed by the machine in a manner similar to that described for the rolling of the core packing.

As shown in Figs. 1 and 2 the engaging edge 31 of the plate or pusher 30 is continuous, but this is not essential and the edge may be serrated or cut away, the only requisite being that the packing roll be engaged from end to end at points which are closely enough spaced to cause the even insertion of the roll at all points in its length.

By the use of my improved machine the time required for producing a roll of packing is greatly reduced, and owing to the even insertion in the machine a roll of uniform hardness throughout results.

Having thus described my invention, what I claim as new and desire to protect by Letters Patent is:

1. In a machine for making rolled packing, means for rolling up a packing strip, and means for uniformly starting the rolling of the strip in the machine throughout the length of the roll.
2. In a machine for making rolled packing, means for rolling up a packing strip on a core disposed at one edge of the strip, and means for giving the strip an initial partial roll on the core.
3. In a machine for making rolled packing, coacting packing rolling elements, and means for evenly introducing a core and packing between them and for giving the same an initial partial roll.
4. In a machine for making rolled pack-

ing, coacting packing rolling elements, means for evenly introducing a core and packing between said elements, and means carried by one of said elements and coacting with said first means to give the core and packing an initial partial roll.

5. In a machine for making rolled packing, means for rolling up a packing strip on a core, means for uniformly starting the 10 rolling strip on the core throughout the length of the latter, and means for adjusting said latter means.

6. In a machine for making rolled packing, means for rolling up a packing strip on 15 a core disposed at one edge of the strip, means for giving the strip an initial partial roll on the core, and means for adjusting said latter means for cores of different diameter.

20 7. In a machine for making rolled packing, coacting packing rolling elements, means for adjusting one of said elements, means for evenly introducing the packing between said elements, and means for adjusting said last named means.

8. In a machine for making rolled packing, a drum, a coacting apron adjustably spaced therefrom, and means for evenly inserting a core and strip of packing between 25 said drum and apron.

9. In a machine for making rolled packing, a drum and a coacting apron between which the rolled up edge of a packing strip may be inserted, and a guide-plate movably carried by the machine for evenly inserting the strip throughout its length between the 35 drum and apron.

10. In a machine for making rolled packing, a drum and a coacting apron between 40 which a core and packing strip may be inserted, a guide-plate movably carried by the machine for evenly inserting the core and strip throughout the length of the core between the drum and apron, and means for 45 varying the point of engagement of the plate with the core.

11. In a machine for making rolled packing, a drum and a coacting apron between which a core and packing strip may be inserted to be rolled, and a pivotally mounted 50 guide-plate for the core, adapted to be swung between the drum and apron.

12. In a machine for making rolled packing, a drum and a coacting apron between 55 which a core and packing strip may be inserted to be rolled, a pivotally mounted guide-plate for the core adapted to be swung between the drum and apron, and means for normally holding the plate away from the 60 drum and apron.

13. In a machine for making rolled packing, a drum and a coacting curved apron between which a packing strip may be inserted to be rolled, a pivotally mounted 65 frame carried by the machine, a guide-

plate secured to one end of the frame and adapted to be swung between the drum and apron, a counter weight on the opposite end of the frame, and means for adjusting the pivotal mounting of the frame.

70

14. In a machine for making rolled packing, a drum, a curved apron adjustably carried in spaced relation to the drum, and a pivotally mounted guide-plate adapted to be 75 swung between said drum and apron.

75

15. In a machine for making rolled packing, a drum, a curved apron spaced from the drum, means for adjusting the ends of the apron to or from the drum, and a pivotally mounted guide-plate adapted to be 80 swung between said drum and apron, the surface of the apron being serrated adjacent the point of entry of the guide-plate.

16. In a machine for making rolled packing, a drum, a curved apron coacting therewith, means for evenly inserting the rolled up edge of a packing strip between the drum and one end of the apron, adjustable means for spacing said end of the apron from the drum, yielding means for spacing the other 85 end of the apron from the drum, and means for adjusting said last named means.

17. In a machine for making rolled packing, a drum, a curved apron, means for adjustably supporting said apron in spaced 90 relation to said drum, means for evenly introducing the rolled up edge of a packing strip between the drum and one end of said apron, and means independent of said drum for yieldingly maintaining the other end of 100 the apron in spaced relation to the drum.

18. In a machine for making rolled packing, a drum, a curved apron, means for adjustably supporting said apron in spaced 105 relation to said drum, means for evenly introducing the rolled up edge of a packing strip between the drum and one end of the apron, means for adjusting said second means, means for yieldingly supporting the other end of the apron in spaced relation 110 to said drum, and means for adjusting said last named means.

19. In a machine for making rolled packing, a main frame, a drum supported therein, a segmental curved apron, means carried by the frame for adjustably supporting the front end of said apron in spaced relation to the drum, chains adjustably mounted in said frame and connected to the rear end of said apron, a frame pivotally mounted 115 on the main frame, and a plate carried thereby and having a rounded edge axially alined with the drum and adapted to be swung between the drum and apron.

20. In a machine for making rolled packing, a rotary drum, a curved apron adjustably supported in spaced relation thereto, the inner surface of said apron being serrated at one end, and means for evenly introducing the rolled up edge of a packing 120

125

130

- strip between said serrated end and the drum, said means comprising a pivotally mounted plate having a rounded front edge adapted to be swung between the apron and drum.
21. In a machine for making roll packing, a rotary drum, an apron spaced therefrom and provided at its front inner face with a gripping surface, and means for initially alining the material between said drum and gripping surface.
22. In a machine for making roll packing, a rotary drum with a curved apron adjustably supported in spaced relation thereto, the inner front surface of said apron being serrated and adapted to cause an instantaneous grip when the machine is started thereby obviating kinking or slipping of the material, and means for wedging said packing between the said serrated surface and 20 drum.
23. In a machine for forming a roll of sheet material having a core along one end thereof, a rotary drum, an apron and mounted means for engaging the core throughout 25 its length for positioning the said core between the drum and apron in axial alinement with the drum.

Signed at New York city, N. Y., this 20th day of December, 1919.

WILLIAM J. KENT.
